(57) CLAIM

The ornamental design for a retractable clothes dryer, as shown and described.

DESCRIPTION

FIG. 1 is a top, front, right side perspective view of a retractable clothes dryer, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front, right side perspective view showing the retractable clothes dryer in use state;

FIG. 10 is a top, rear, left side perspective view thereof; and,

FIG. 11 is an enlarged view of portion 11 in FIG. 1.

The broken lines illustrate portions of the retractable clothes dryer and depict environment of the claim that forms no part of the claimed design. The dot-dash-dot broken lines define the boundaries of enlarged views and form no part of the claimed design.
